Primary Examiner—Alan P. Douglas*Assistant Examiner*—Robin V. Taylor*Attorney, Agent, or Firm*—Myron B. Kapustij; Leon E. Redman[57] **CLAIM**

The ornamental design for a showerhead, as shown and described.

DESCRIPTION

FIG. 1 is a front perspective view of a showerhead showing my new design;

FIG. 2 is a rear perspective view thereof;

FIG. 3 is a front elevational view thereof;

FIG. 4 is a side elevational view thereof, the opposite side being a mirror image;

FIG. 5 is a rear elevational view thereof; and,

FIG. 6 is a side elevational view similar to FIG. 4 except with the showerhead rotated 90° relative to its position in FIG. 4, the other side being a mirror image.
